UNITED STATES PATENT OFFICE.

DAVID L. GRAFF, OF NEW YORK, N. Y.

DESIGN FOR A SMOKER'S OUTFIT.

52,736.

Specification for Design.

Patented Dec. 10, 1918.

Application filed August 14, 1918. Serial No. 249,917. Term of patent 7 years.

To all whom it may concern:

Be it known that I, DAVID L. GRAFF, a citizen of the United States, residing at New York city, in the county and State of New York, have invented a new, original, and ornamental Design for a Smoker's Outfit, of which the following is a specification, reference being had to the accompanying drawings, forming a part thereof, and in which—

Fig. 2 a front view, and
Fig. 3 a top view of a smoker's outfit embodying my design.

I claim:

The ornamental design for a smoker's outfit, as shown.

DAVID L. GRAFF.

Witnesses:

ARTHUR MARION,
CHAS. C. GILL.
